UNITED STATES PATENT OFFICE.

ARTHUR E. SNOW, OF CINCINNATI, OHIO, ASSIGNOR TO THE DALY MANUFACTURING COMPANY, OF CINCINNATI, OHIO, A CORPORATION OF OHIO.

GARMENT-PRESSING DEVICE.

Application filed May 24, 1923. Serial No. 641,239.

To all whom it may concern:

Be it known that I, ARTHUR E. SNOW, a citizen of the United States of America, and a resident of Cincinnati, in the county of Hamilton and State of Ohio, have invented a new and useful Improvement in a Garment-Pressing Device, of which the following is a specification.

An object of my invention is to provide a garment pressing device in which continued pressure may be exerted upon a garment without necessitating a continued expenditure of energy by the user.

Another object of my invention is to provide a presser device that will automatically adjust itself to various thicknesses of materials operated upon.

Another object is to provide a device of this kind which is simple and efficient.

Another object is to provide such a device having a minimum of movable parts.

Fig. 1 is a frontal perspective of a device of my invention.

Fig. 2 is a side elevation of the same.

Fig. 3 is a fragmental view of Fig. 2, parts being broken away.

Fig. 4 is a fragmental perspective showing a detail of my device.

Fig. 5 is an enlarged sectional view on line 5—5 of Fig. 1.

Fig. 6 is an enlarged sectional view on line 6—6 of Fig. 2.

My invention comprises a base 5 upon which is mounted a table 7 and a buck 8. The base 5 has its upper portion developed into two uprights 9 and 10 which extend to a height substantially equal to that of the buck 8. A presser arm 11 is pivotally mounted intermediate its ends upon the uprights 9 and 10. The ends of the presser arm 11 carry the presser head 12, and balance weight 14 which serves to normally retain the presser head 12 in a raised position.

The particular features of my invention lie in the hereinafter described mechanism. A foot lever 15 is pivotally mounted intermediate its ends upon the base 5 and has a pedal plate 16 at its one end positioned at the front of the device so as to be conveniently accessible to the foot of the user. A slotted yoke 17 pivotally mounted upon the base 5 at the rear thereof carries a forwardly extending arm 18. A link 19 has its ends pivotally mounted upon the

arm 18 and the rearward end of the foot lever 15. The yoke 17 has aligned longitudinal bores thru its ends, thru which bores is reciprocally mounted a rod 20. A spring 21 surrounds the rod and abuts the lower end of the yoke 17. A flange 220 on the rod 20 serves as an abutment for the other end of the spring 21. The upper end of the rod 20 has mounted upon it a coupling or block 22 which is capable of limited longitudinal adjustment by such means as a nut 23. The nut 6 on the lower end of rod 20 provides adjustment for the spring 21. The link 24 pivotally connects the coupling or block 22 and the presser arm 11. The foot lever 15 carries a stud 25 upon which a hook 26 may engage for holding the lever 15 in a locked position. The pedal 27 serves to release the hook 26. The finger 28 serves to render the hook 26 operative or inoperative upon the stud 25. Any other suitable latch device may be utilized in lieu of the foregoing, for example the device as shown in the patent to Andree #1,403,826.

Steam for heating the presser is generated in the tank 29 and is piped into the presser head 12 thru the usual swivel connections 30. Steam to be emitted thru the upper face of the buck 8 is controlled by means of a valve of the ordinary type and is controlled by the rod 31 which is operated by the foot lever 32. A garment may be steamed by means of the puff 33, the steam being taken from the presser head 12 and controlled by a manually operated valve 34.

In operation a garment is placed upon the buck 8 and is steamed by pressing down upon the foot lever 32. By pressing downward on the pedal 16 the lever 15 is moved on its pivotal mounting by which movement the yoke 17 and rod 20 are brought into alignment with the link 24 thru the agency of the link 19 and arm 18 on the yoke. This movement raises the rearward end of the presser arm 11 and brings the presser head 12 downward onto the buck 8. When the rod 20 and the link 24 are aligned the end of the rod 20 is moved against the yielding resistance of the spring 21. The lever 15 may then be locked in its lowered position by means of stud 25 and hook 26 at which time the pressure exerted on the buck is supplied entirely by the spring 21. (See Fig. 2.) The pressure exerted on the garment may be modified by adjusting the nut 116

6 at the lower end of rod 20. When the hook 26 is released and pressure is removed from the foot lever 15 a tension spring 35 returns the yoke 17 and link 24 to their normal positions as shown in Fig. 3. From the foregoing it will be apparent that the spring 21 permits automatic adjustment of the device to the thickness of the material pressed.

The puff iron 33, carried by the presser head affords a readily accessible means for use when the presser head is in a locked position. Previously steam was emitted from the presser head in pressing the shoulder portion of a coat. However, this was necessarily done with the head in a raised position and provided a rather unstable and unaccessible means, and as the steam issued from the entire face of the presser head this method was wasteful of steam. The puff 20 33 is designed to overcome these difficulties.

What I claim is:

1. In a garment press the combination of a base, an elongated yoke having its one end pivotally mounted upon the base at the rear thereof, said pivoted end of the yoke being provided with a forwardly extending arm, the ends of the yoke being provided with aligned bores, a rod reciprocally received in the bores in the yoke, a washer 25 30 mounted on the rod intermediate the ends of the yoke, a spring extending about the rod

and having its opposite ends in engagement upon the washer and the pivotally mounted end of the yoke, a presser arm pivotally supported by the base, a link pivotally connecting one end of the presser arm and the end of the rod adjacent the free end of the yoke, a foot lever pivotally mounted intermediate its ends at the front of the base, and a link pivotally connecting the arm on the 40 yoke and one end of the foot lever.

2. In a garment press the combination of a base, an elongated yoke having its one end pivotally mounted upon the base, said pivoted end of the yoke being provided with an outwardly extending arm, the ends of the yoke being provided with aligned bores, a rod reciprocally received in the bores in the yoke, a spring operative upon the rod and the yoke yieldingly resisting movement 50 of the rod through the aligned bores, a presser arm pivotally supported by the base, a link pivotally connecting the presser arm and the end of the rod adjacent the free end of the yoke, a foot lever pivotally mounted 55 on the base, and a link pivotally connecting the arm on the yoke and one end of the foot lever.

In testimony whereof, I have hereunto subscribed my name this 10th day of May, 60 1923.

ARTHUR E. SNOW.
